DESIGN FOR A COMBINED STAND AND INDUCTION DEVICE HOLDER FOR TELE- PHONES

Charles W. Dann, Orange, N. J., assignor to
Thomas A. Edison, Incorporated, West Orange,
N. J., a corporation of New Jersey

Application April 1, 1944, Serial No. 113,107

Term of patent 14 years

(Cl. D26—14)

To all whom it may concern:

Be it known that I, Charles W. Dann, a citizen
of the United States, residing at Orange, in the
county of Essex and State of New Jersey, have
invented a new, original, and ornamental Design
for a Combined Stand and Induction Device
Holder for Telephones, of which the following is
a specification, reference being had to the accom-
panying drawing, forming part thereof.

Figure 1 is a perspective view of a combined

stand and induction device holder for telephones
showing my new design.

Figure 2 is a view thereof in side elevation.

Figure 3 is a view thereof in front elevation.

I claim:

The ornamental design for a combined stand
and induction device holder for telephones, sub-
stantially as shown.

CHARLES W. DANN.
